UNITED STATES PATENT OFFICE.

JUDSON R. RUPE, OF STURGIS, MICHIGAN, ASSIGNOR TO CENTRAL WHEEL COMPANY,
OF STURGIS, MICHIGAN, A CORPORATION OF MICHIGAN.

WIRE WHEEL.

1,411,382.

Specification of Letters Patent.

Patented Apr. 4, 1922.

Application filed May 28, 1920. Serial No. 384,960.

To all whom it may concern:

Be it known that I, JUDSON R. RUPE, a citizen of the United States, residing at Sturgis, county of St. Joseph, State of Michigan, have invented certain new and useful Improvements in Wire Wheels, of which the following is a specification.

This invention relates to improvements in wire wheels. It relates particularly to improvements in the hub part.

The object of the invention is to provide a very simple and staunch hub in which the parts are effectively locked against accidental displacement.

Objects pertaining to details of the structure will definitely appear from the detailed description to follow.

I accomplish the objects of the invention by the devices and means described in the following specification. The invention is clearly defined and pointed out in the claims.

A structure which is a preferred embodiment of my invention is fully illustrated, so far as the hub structure is concerned, in the accompanying drawing forming a part of this specification, in which:

Fig. I is a detail perspective view of the hub part of a wheel, a portion of the barrel being cut away to show details of construction.

Fig. II is a transverse detail sectional perspective view through the hub near one end.

Fig. III is a detail elevation view of one end of the hub barrel.

Fig. IV is a detail longitudinal sectional view taken on line corresponding to line 4—4 of Fig. II, showing details of the locking means.

Fig. V is a detail sectional elevation view similar to that of Fig. IV, showing the structure slightly modified.

In the drawing similar numerals of reference refer to similar parts throughout the several views, and the sectional view is taken looking in the direction of the little arrows at the ends of the section line.

Considering the numbered parts of the drawing, 1 is the barrel of the hub which is notched at its end as indicated at 2, forming a series of projecting lugs 3 and 4. 5 is one of the looped double wire spokes. These are retained on the end flange of the hub by clip pieces 7 wrapped therearound. The hub barrel 1 is inserted into the flange, each lug 3 extends between a pair of spokes, and

each lug 4 extends into the loop of a corresponding double spoke. The flange is folded over the barrel 1 at 8 and effectively embraces and caps over the same, closing up any gap at that point and presenting a nicely finished appearance as well. There is then inserted the locking bearing tube 10 into the hub and a collar 9 is disposed on this tube 10 and is suitably flanged for the wheel attaching devices where the wheels are made detachable. The locking tube 10 is provided with a longitudinal rib 11 which is struck up therefrom, which engages in a notch 12 in the flange 6. The locking tube 10 is expanded at 13 and 14 by spinning and locks the two head flanges of the hub securely together. Because of the projecting rib 11 the parts are locked against turning upon each other and remain permanently in position. This results in a very staunch wheel in which the spokes at the two ends of the hub are effectively located in alternate position to effectively support the rim.

Where the wheel is not made detachable, the collar 9 is simply omitted and the end 13 is spun the same as the end 14. Where it is desired to make a wheel of extra strength, the projecting rib may be extended the entire length of the locking bearing tube, as appears at 15 in Fig. V, the same engaging a notch 16 at the end, as there indicated.

From this description and examination of the parts, it will be seen that a wheel is provided with a complete hub barrel which effectively engages and spaces all of the spokes. The end flanges or plates are locked securely in position and because of the projections 8 between the spokes 6 a complete finished hub is produced. The parts are maintained in relative position from turning axially on each other by the rib 11, a matter of very great consequence in securing a staunch wheel. The rib 11 is also of great advantage in retaining the collar effectively and strongly in position. The inverted groove of this rib is of value in retaining lubricant.

Having thus described my invention, what I claim as new and desire to secure by Letters Patent is:

1. In a wheel structure the combination of double spokes, a hub barrel therefor notched to form lugs to project within the loops of the spoke and between the same, flanges for the said hub having clip portions

- to engage the spokes and inturned portions between the spokes and to engage the loops thereof, a flanged collar at each end of the hub, one collar and one flange being suitably notched axially, and a bearing and locking tube with longitudinal rib expanded and spun into the said wheel to form the central bearing and retain the parts locked in position, as specified.
- 10 2. In a wheel structure the combination of double spokes, a hub barrel therefor notched to form lugs to project within the loops of the spoke and between the same, flanges for the said hub having clip portions 15 to engage the spokes and inturned portions between the spokes and to engage the loops thereof, one of said flanges being suitably notched axially, and a bearing locking tube with longitudinal rib expanded and spun 20 into the said wheel to form the central bearing and retain the parts locked in position, as specified.
3. In a wheel structure the combination of double spokes, a hub barrel therefor notched to form lugs for engaging the said spokes, flanges for the said hub having clip portions embracing the said spokes, a flanged collar at each end of the hub, one 25 collar and one flange being suitably notched 30 at the center, and a bearing locking tube

with longitudinal rib the ends of which are spun into the said flanges to form the central bearing and retain the parts locked in position, as specified.

4. In a wheel structure the combination of 35 double spokes, a hub barrel therefor notched to form lugs for engaging the said spokes, flanges for said hub having clip portions embracing the said spokes, one of said flanges being suitably notched at the center, 40 and a bearing locking tube with longitudinal rib the ends of which are spun into the said flanges to form a central bearing and retain the parts locked in position, as specified.

5. In a wheel structure the combination of 45 double spokes, a hub barrel, flanges for the said hub having portions embracing the said spokes, one of said flanges being suitably notched at the center, and a bearing locking tube with longitudinal rib the ends of which 50 are spun into the said flanges to form the central bearing and retain the parts locked in position, as specified.

In witness whereof, I have hereunto set my hand and seal in the presence of two witnesses.

JUDSON R. RUPE. [L.S.]
